HEAT EXCHANGER

Arthur J. Fausek and Irving F. Fausek,
Clayton, Mo.

Application November 16, 1944, Serial No. 563,647

4 Claims. (Cl. 257—246)

1

This invention relates generally to heat exchangers, and more specifically to heat exchangers of the type comprising a structure which includes a plurality of independent passageways through which pass fluid, gas, or other mediums, whose temperatures are to be changed, the predominant object of the invention being to provide a heat exchanger of type mentioned which is of extremely simple and relatively inexpensive construction and arrangement, and which is capable of performing its intended function in a highly efficient manner.

Fig. 1 is a view partly in vertical section and partly in elevation illustrating the improved heat exchanger.

Fig. 2 is a fragmentary vertical sectional view of a portion of the heat exchanger illustrated in Fig. 1.

Fig. 3 is a view similar to Fig. 2 but illustrating a slightly modified form of the invention.

Fig. 4 is a fragmentary vertical section showing still another modified form of the invention.

Fig. 5 is a fragmentary vertical section illustrating yet another form of the invention.

Fig. 6 is a fragmentary vertical section showing the heat exchanger of Fig. 1 when provision is made for passage through the heat exchanger of an additional medium.

In the drawing, wherein are illustrated for purposes of illustration, merely, several embodiments of the invention, A designates in Fig. 1 the improved heat exchanger generally. The heat exchanger A comprises an outer, cylindrical housing 1 which is closed at its top and bottom by closure members 2 and 3 which are suitably secured in place. Adjacent to its upper end the outer housing 1 is provided with an inlet conductor 4 which communicates with the interior of said outer housing and which is adapted to deliver into said outer housing one of the mediums whose temperature is to be changed during passage through the heat exchanger, said outer housing being provided also with an outlet conductor 5 which is located adjacent to the lower end thereof in communication with the interior of said outer housing and through which such medium is discharged from the outer housing after passage therethrough.

Disposed within the outer housing 1 of the heat exchanger A, and extended longitudinally thereof, is an inner tubular member 6, said inner tubular member being shown in Fig. 1 as having tapered opposite ends, an inlet conductor 7 and an outlet conductor 8 being formed on said inner, tubular member or suitably secured thereto, and said inlet

2

conductor 7 and said outlet conductor 8 being extended through apertures formed through the closure members 2 and 3 of the outer housing 1. The wall of the inner tubular member is spaced from the wall of the outer housing 1, and as will presently appear herein in more detail, the inner tubular member 6 provides a passageway through the heat exchanger for one of the mediums whose temperature is changed during its passage through the heat exchanger.

Arranged within the outer housing 1 and disposed in embracing relation with respect to the inner tubular member 6 is a spirally corrugated, intermediate, tubular member 9. The depth of the corrugations of the intermediate tubular member is such that the inner curved faces of said corrugations contact closely with the outer face of the wall of the inner tubular member 6, while the outer curved faces of said corrugations of said intermediate tubular member contact closely with the inner face of the wall of the outer housing 1 (Fig. 2).

Because of this arrangement the corrugations of the intermediate tubular member 9 provide two spiral passageways through the heat exchanger 1, one such spiral passageway, which is designated by the reference character 10, being formed by the convex, spiral portion 9a of the corrugations and an adjacent, spiral portion 6c of the outer face of the inner tubular member 6, and the other spiral passageway, which is designated by the reference character 11, being formed by the concave, spiral portion 9b of the corrugations and an adjacent spiral portion 1a of the inner face of the outer housing 1. The intermediate tubular member 9 has associated therewith an inlet conductor 12 which extends through an aperture formed through the wall of the outer housing 1 and which is welded, or otherwise secured, to said intermediate tubular member in communication with the spiral passageway 10. In like manner, the intermediate tubular member 9 has associated therewith an outlet conductor 13 which is welded, or otherwise secured, to said intermediate tubular member in communication with the spiral passageway 10 at the end remote from the end at which the inlet conductor 12 is located, said outlet conductor 13 being extended through an opening formed through the wall of the outer housing 1.

In the use of the improved heat exchanger disclosed in Figs. 1 and 2, one medium enters the outer housing 1 of the heat exchanger by way of the inlet conductor 4 and passes in a spiral manner through the spiral passageway 11 provided

by the concave, spiral portion of the intermediate tubular member 9, and an adjacent spiral portion of the inner face of the wall of the outer housing 1, such medium being discharged from the heat exchanger by way of the outlet conductor 5. In like manner, another medium passes into the spiral passageway 10 provided by the convex, spiral portion of the intermediate tubular member and an adjacent spiral portion of the outer face of the wall of the inner tubular member 6, said medium passing spirally through said passageway and being discharged from the heat exchanger by way of the outlet conductor 13. Still another medium passes through the inner tubular member 6, the last-mentioned medium entering the inner tubular member by way of the inlet conductor 7 and being discharged from said inner tubular member by way of the outlet conductor 8. Thus it is apparent that efficient interchange of temperatures of the three mediums is accomplished during their passage through the various passageways of the heat interchanger in an obvious and well known manner.

In Fig. 3 a structure is illustrated which is quite similar to the structure illustrated in Fig. 2. However, the inner tubular member 14 of Fig. 3 has formed thereon, or fixed thereto, a spiral fin 15 which extends outwardly from said inner tubular member into the spiral passageway 16, which corresponds to the spiral passageway 10 of Fig. 2. The use of the spiral fin 15 increases the efficiency of the heat exchanger in that it causes temperature conducting faces to be disposed in the core of the medium passing through the passageway 16 where temperature conductivity is ordinarily poor.

Fig. 4 illustrates a structure resembling the structure of Fig. 2 except that the structure of Fig. 4 includes a rod 17 which is extended spirally through the spiral passageway 18 at the base thereof. While the particular rod illustrated in Fig. 4 is semicircular in cross-sectional shape, and its main purpose is to give strength and rigidity to the structure. If desired the rod 17 may be soldered, brazed, or otherwise secured in place.

The structure of Fig. 5 is quite similar to the structure of Fig. 3, the only difference between the structures of said views being that the inner tubular member 19 of Fig. 5 has arranged longitudinally therein a rod 20 on which is formed, or fixed, a spiral fin 21. The outer edge of the spiral fin 21 contacts closely with the inner face of the wall of the inner tubular member, and said spiral fin provides a spiral passageway through said inner tubular member for the medium passing therethrough.

The heat exchanger illustrated in Figs. 1 and 2 is adapted for the passage therethrough of three mediums whose temperatures are to be changed during passage of said three mediums through the heat exchanger. If it should be desired to increase the capacity of the heat exchanger of Figs. 1 and 2 so that four mediums may be passed therethrough, this may be accomplished by adding to the structure of Figs. 1 and 2 an additional spirally corrugated, tubular member 22, as is shown in Fig. 6. In Fig. 6 the spirally corrugated, tubular member 22 is shown as embracing the housing 1' of the structure with the wall of the depressed, spiral portion of said member contacting with the outer face of the wall of said housing 1'. The convex spiral portion of the member 22 and a spiral portion of the outer face of the wall of the hous-

ing 1' provide a spiral passageway 23 through which the additional medium passes, and said spiral passageway 23 is provided with an inlet conductor 24 and an outlet conductor 25 which lead to and from said spiral passageway 23.

We claim:

1. A heat exchanger comprising an elongated housing which is closed at its opposite ends, an inlet conductor and an outlet conductor leading to and from the interior of said housing respectively, an inner tubular member extended longitudinally through said housing with the wall of said inner tubular member spaced from the wall of said housing, inlet and outlet conductors leading to and from said inner tubular member respectively for passage through said inner tubular member of a medium, an intermediate spirally corrugated tubular member disposed in the space between the wall of said inner tubular member and the wall of said housing, said spirally corrugated intermediate tubular member having a convex spirally extended corrugation portion which contacts with the inner face of the wall of said housing and a concave spirally extended corrugation portion which contacts with the outer face of the wall of said inner tubular member, whereby one spiral passageway is provided through the heat exchanger by a spiral of said intermediate tubular member and an adjacent spiral portion of the outer face of the wall of said inner tubular member, and a second spiral passageway is provided through the heat exchanger by a spiral portion of said intermediate member and an adjacent spiral portion of the inner face of the wall of said housing, said spiral passageway formed by a portion of said intermediate tubular member and a portion of the wall of said housing communicating directly with the interior of said housing for passage therethrough of medium which enters said housing, inlet and outlet conductors leading to and from the other of said spiral passageways respectively for passage through said other spiral passageway of another medium, and a spiral element arranged in one of said spiral passageways.
2. A heat exchanger comprising an elongated housing which is closed at its opposite ends, an inlet conductor and an outlet conductor leading to and from the interior of said housing respectively, an inner tubular member extended longitudinally through said housing with the wall of said inner tubular member spaced from the wall of said housing, inlet and outlet conductors leading to and from said inner tubular member respectively for passage through said inner tubular member of a medium, an intermediate spirally corrugated tubular member disposed in the space between the wall of said inner tubular member and the wall of said housing, said spirally corrugated intermediate tubular member having a convex spirally extended corrugation portion which contacts with the inner face of the wall of said housing and a concave spirally extended corrugation portion which contacts with the outer face of the wall of said inner tubular member, whereby one spiral passageway is provided through the heat exchanger by a spiral portion of said intermediate tubular member and an adjacent spiral portion of the outer face of the wall of said inner tubular member, and a second spiral passageway is provided through the heat exchanger by a spiral portion of said intermediate member and an adjacent spiral portion of the inner face of the wall of said housing, said spiral passageway formed by a portion of said intermediate tubular member

and a portion of the wall of said housing communicating directly with the interior of said housing for passage therethrough of medium which enters said housing, inlet and outlet conductors leading to and from the other of said spiral passageways respectively for passage through said other spiral passageway of another medium, and a spiral fin disposed in said spiral passageway which is formed by a portion of said intermediate tubular member and a portion of said inner tubular member.

3. A heat exchanger comprising an elongated housing which is closed at its opposite ends, an inlet conductor and an outlet conductor leading to and from the interior of said housing respectively, an inner tubular member extended longitudinally through said housing with the wall of said inner tubular member spaced from the wall of said housing, inlet and outlet conductors leading to and from said inner tubular member respectively for passage through said inner tubular member of a medium, an intermediate spirally corrugated tubular member disposed in the space between the wall of said inner tubular member and the wall of said housing, said spirally corrugated intermediate tubular member having a convex spirally extended corrugation portion which contacts with the inner face of the wall of said housing and a concave spirally extended corrugation portion which contacts with the outer face of the wall of said inner tubular member, whereby one spiral passageway is provided through the heat exchanger by a spiral portion of said intermediate tubular member and an adjacent spiral portion of the outer face of the wall of said inner tubular member, and a second spiral passageway is provided through the heat exchanger by a spiral portion of said intermediate member and an adjacent spiral portion of the inner face of the wall of said housing, said spiral passageway formed by a portion of said intermediate tubular member and a portion of the wall of said housing communicating directly with the interior of said housing for passage therethrough of medium which enters said housing, inlet and outlet conductors leading to and from the other of said spiral passageways respectively for passage through said other spiral passageway of another medium, and a spiral fin supported by said inner member and disposed in said spiral passageway which is formed by a portion of said intermediate tubular member and a portion of said inner tubular member.

4. A heat exchanger comprising an elongated housing which is closed at its opposite ends, an inlet conductor and an outlet conductor leading

to and from the interior of said housing respectively, an inner tubular member extended longitudinally through said housing with the wall of said inner tubular member spaced from the wall of said housing, inlet and outlet conductors leading to and from said inner tubular member respectively for passage through said inner tubular member of a medium, an intermediate spirally corrugated tubular member disposed in the space between the wall of said inner tubular member and the wall of said housing, said spirally corrugated intermediate tubular member having a convex spirally extended corrugation portion which contacts with the inner face of the wall of said housing and a concave spirally extended corrugation portion which contacts with the outer face of the wall of said inner tubular member, whereby one spiral passageway is provided through the heat exchanger by a spiral portion of said intermediate tubular member and an adjacent spiral portion of the outer face of the wall of said inner tubular member, and a second spiral passageway is provided through the heat exchanger by a spiral portion of said intermediate member and an adjacent spiral portion of the inner face of the wall of said housing, said spiral passageway formed by a portion of said intermediate tubular member and a portion of the wall of said housing communicating directly with the interior of said housing for passage therethrough of medium which enters said housing, inlet and outlet conductors leading to and from the other of said spiral passageways respectively for passage through said other spiral passageway of another medium, a spiral element arranged in one of said spiral passageways and a spiral structure disposed within said inner tubular member and extended longitudinally thereof.
